GAME

Charles F. Kuehne, Jersey City, N. J.

Application July 26, 1938, Serial No. 221,278

11 Claims. (Cl. 273—94)

This invention relates to games and specifically to a game board.

In general, it is an object of the invention to provide a device of the character described, which will efficiently perform the purposes for which it is intended, which is simple and economical of construction, which can be expeditiously and conveniently manipulated, and which can be readily manufactured and assembled.

Another object of the invention is to provide a game board which with one setting indicates the result of a play, whether that play is of one predetermined type or another, the result being indicated as different for different opponents or players and which may or may not have a chance-controlled element, attached to the board, for selecting which one in the set is to be considered to have occurred; which may simulate a game normally not played on a board; which may have an element simulating a real element in the real game and determining by its position the status above referred to; and which for any period of the game indicates a particular set of possible results for the same type of play, which set depends upon the status in the game of the player making the play but the same set for any player at any time having that particular status.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawing, in which:

Figure 1 is a plan view, with portions broken away, of a device embodying one form of the invention; and

Fig. 2 is a cross-section of the device shown in Fig. 1 and taken along the line 2—2.

In the drawing, 110 denotes a frame which carries a game board 112 of any suitable material. Indicia on the board may convey the idea of any game and its progress. The game may be new or old. It may simulate a game normally not played on a board, e. g., as is shown in Fig. 1, a football field.

Means are provided showing different types

of plays and different possible results for each type. These may take any convenient form. Preferably the device has available different groups of possible results from which one result is determined to be the one by which the game is advanced. In the example in the drawing, there are twelve possible results visible at any one time for each type of play.

As shown, there are seven types of play each assigned to an opening 114 in the board through which are visible various possible results for each type. The openings are respectively labeled "Kick offs and punts," "Return of kick off, punts, interceptions, fumbles, attempted field goals," "Line-end and lateral plays," "Forward passes," "Try for field goal," "Try for point after touchdown" and "Penalty." Adjacent each opening there is a series of numbers fixedly positioned on the board and beginning with the numeral one. There are as many numbers as there are possible results visible at any one time through the adjacent opening. As shown, there are twelve such possible results. There is a similar series with each opening but, for purposes of clarity, not all of the series are shown on the drawing. Preferably there are openings labeled as above for one player or opponent and other similar openings for each additional player or opponent.

Means are provided for moving one set of possible results into registry with the said numerals but beneath the opening and for replacing that set with another set. There may be a plurality of such sets. These sets may be brought, by means to be described, successively into view. Any group of possible results which happens to be visible may be considered a set. Thus, any one result may lie within the boundaries of different sets as they are successively moved into view. Shafts 116 are supported by the frame 110 and extend beneath and parallel to the board 112. They are rotatable by knobs 118 on the ends of the shafts and outside of the frame 110. A sheet 120 is wound on the shafts and extends parallel to and beneath the board 112. The various possible results are written down on the sheet 120 in such position that they are successively visible through the openings 114 and so that one result is in registry with each of the numerals which are fixed on the board 112. They are spaced at the same distance as the said numerals are spaced. These results are not shown on the drawing except by parallel lines 122 between each two of which

a single is placed. These lines assist in registering the results with the numerals.

There may be an element associated with the game and shown on the board such as the football 124 which, by its position, shows the progress of the game or the relative status of the opponents. Means may be provided for causing a particular set of possible results to be shown respectively for each type of play, depending upon the position of the element 124. Thus, that element may be connected, through an opening 126 in the board, to the sheet 120. The opening 126 in the game shown extends centrally the length of the field. When element 15 124 is near the center of the field, as at the beginning of play, a set of twelve possible results, which are shown through the opening labeled "Kick offs and punts," may read, for example: touchback, 22 yards, 35 yards, 50 yards, 20 touchback, 33 yards, 43 yards, 41 yards, 29 yards, 36 yards, 54 yards, and 39 yards. Each of these twelve possible results is accurately aligned with one of the numerals from 1 to 12 mentioned above.

25 Any desirable means may be used for determining which of the twelve possible results is to be the one considered to occur in the game. Chance means may be used. These may take the form of dice or the spinning arrow 128 attached to the board, the tip of which arrow passes over a circle having the numerals 1 to 12 placed thereon.

To begin the game, the football 124 is placed on the forty-yard line of the player who is to kick off, who then spins the arrow 128. The tip of the arrow will come to rest on some numeral, say 4. Next, it is observed what result is shown through the opening entitled "Kick offs and punts" and associated with the numeral 4. Using the above set of possible results for the kick-off, it is seen that the team A kicking off accomplished the carrying forward of the ball thereby through fifty yards. Next, the ball is moved, by the turning of the handles 118, to the 10-yard line of the defending team B. The player representing team 40 B then spins the arrow until it comes to rest at say 10. He then looks through the opening assigned to team B and entitled "Return of kick offs, etc." and notes that the possible result associated with the numeral 10 shows that team B returns the kick-off by team A nine yards to team B's 19-yard line. The ball 124 is moved to the 19-yard line of team B and the player representing that team again spins the arrow which comes to rest at say 6. Whereupon the player representing team B refers to the set of possible results through the opening entitled "Line-end and lateral plays," assuming that that is the type of play which player B chooses to make. He is free to choose any type of play he wishes, announcing his selection before he plays. The play of the game is continued in accordance with the usual rules of football to the conclusion of the game. The length of the game may be limited to a certain period of time or to a certain number 45 of plays. All possible results of any type of play are found somewhere on sheet 120 so that each appears through some one or more of the openings 114 for at least one position of the ball 124. Thus, in the opening 114 entitled "Try for field 50 goal," one of the results is "Blocked." Another is "Fumble." Still another is "Good," which means that the goal was accomplished. In the opening 112 marked "Forward passes," one of the results may be "Intercepted" and another "Goal." 55 One of the results for any type of play is "Penal-

ty." When that is shown in registry with the number indicated by the spinner, reference is then made to the opening entitled "Penalty" and the appropriate penalty there read off under the corresponding number.

5 Means may be provided for showing the number of downs, such as the indicia 130. There may also be indicia 132 on the board, shown without index, for indicating the total score of each team. Also, there may be indicia 134 on the board for 10 indicating the quarter of the game being played.

At any one time there are results shown through the various openings 114 for each team. While one team is attempting to advance the ball, only those results are used which are shown 15 through the openings assigned to that team. At any time, however, when the ball changes hands, the results of a given play are ready and available to be read through the openings assigned to the other team. It is preferred to have each set of 20 possible results, which are visible for the respective positions of the ball, as being such that they correspond in probability with results which are usually present in the playing of an actual game when the ball is in that respective position. For 25 example, when a team has the ball close to its opponent's goal, the results shown preferably include relatively small advances, if any. On the other hand, however, if the ball changes hands on that same line, the possible results shown for 30 the other team which now has the ball include relatively large advances. But, if the last-mentioned team moves down the field to the other 5-yard line, then the results possible and shown through the openings assigned to the other team 35 also include few large advances. In other words, the possible results shown for each team for the same relative position on the field are preferably the same.

It should be understood that the invention is 40 not limited to the game shown in the drawing but may also be used in connection with other games, such as baseball and the like.

Since certain changes may be made in the 45 above construction and different embodiments of the invention could be made without departing from the scope thereof, it is intended that all matter contained in the above description or shown in the accompanying drawing shall be interpreted as illustrative and not in a limiting 50 sense.

It is also to be understood that the following 55 claims are intended to cover all the generic and specific features herein described and all statements of the scope of the invention which, as a matter of language, might be said to fall therebetween.

Having described my invention, what I claim as new and desire to secure by Letters Patent is:

1. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, and means for moving said carrying means, there being indicia associated respectively with each of said openings and differ- 75

ing from the indicia associated with the others of said openings.

2. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, means which allow movement of said movable carrying means and which are mechanically related to said game board by being a part thereof, and means, permanently associated with said combination, for moving said carrying means, there being indicia associated respectively with each of said openings and differing from the indicia associated with the others of said openings.

25 3. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, means, permanently associated with said combination, for moving said carrying means, said carrying means being a sheet of material, and rollers for said sheet to be passed around, said sheet being passed around said rollers, said rollers being supported by said board, there being indicia associated respectively with each of said openings and differing from the indicia associated with the others of said openings.

40 4. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, means for moving said carrying means, said carrying means being a sheet of material, and rollers for said sheet to be passed around, said sheet being passed around said rollers, there being indicia associated respectively with each of said openings and differing from the indicia associated with the others of said openings.

45 5. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying

means being movable so as, in one position, to display, in registry with said indices, a part of said results through each of said openings and in another position to display, in registry with said indices, another part of said results through each of said openings, and means for moving said carrying means, said carrying means being connected to said movable game element whereby whenever said element is in a predetermined position the same predetermined play results are shown through said openings.

50 6. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, and means for moving said carrying means, different ones of said openings being for respectively different types of plays, there being indicia associated with each opening indicating the type of play respective to the opening, and the play results shown through the openings being respectively appropriate to the respective types of plays.

55 7. In combination, a game board having openings therein, a game element movable with respect to the surface of said board, markings on said board associated with the position of said element, a plurality of similar indices adjacent each of said openings, carrying means beneath each of said openings and having a plurality of play results associated therewith, said carrying means being movable so as, in one position, to display, in registry with said indices, a part of said results through each of said openings and in another position to display, in registry with said indices, another part of said results through each of said openings, means for moving said carrying means, said carrying means being connected to said movable game element whereby whenever said element is in a predetermined position the same predetermined play results are shown through said openings, different ones of said openings being for respectively different types of plays and the play results shown through the openings being respectively appropriate to the respective types of plays.

60 8. In combination, a game board, a game element movable with respect thereto, a plurality of indices, a plurality of means each indicating a step in the game, the last-mentioned plurality being variously positionable with respect to said indices and variously positionable in dependence upon the position of said game element, said board having openings whereby said step-indicating means may be observed, and means for holding the plurality of step indicating means, said game board concealing such of said indicating means as are not associated with said indices.

65 9. In combination, a game board, a game element movable with respect thereto, means providing a plurality of openings in said board, a plurality of indices associated with each opening, and a movable sheet mechanically associated with said element whereby said sheet moves when said

game element moves and having a plurality of indicated, possible steps in the game so positioned that as said sheet is moved said steps are each associated with predetermined ones of said indices, said steps having been originally so fixed upon that as said element is moved in the progress of the game those steps which are associated with said indices are steps which are logical for that period of the game in which said element is in that position in which it is.

10. In combination, a game board, a game element movable with respect thereto, means providing a plurality of openings in said board, a plurality of indices associated with said openings, 15 a movable sheet mechanically associated with said element whereby said sheet moves when said game element moves and having a plurality of indicated, possible steps in the game so positioned that as said sheet is moved said steps are each

successively associated with predetermined ones of said indices, and means for moving said element and said sheet together.

11. In a game board, the combination comprising a game element, means operable at a single setting and adapted for indicating possible results of every type of play from a plurality of possible types of play, and means for indicating a particular set of said possible results, said set being dependent upon and continuously variable 10 with the status in the game of the opponent making the play as shown by said element, said operable means being mechanically connected to said game element whereby a change in position of said element causes a change in position of said operable means to a position such that said indicating means indicate a particular set of possible results.

CHARLES F. KUEHNE.
